TOY RACING TRACKWAY

Shizuka Kojima, Tokyo, Japan, assignor to
Tomy Kogyo Co., Inc., Tokyo, Japan

Filed Feb. 5, 1974, Ser. No. 439,752

Term of patent 14 years

Int. Cl. D21—01

U.S. Cl. D34—5 CC

FIG. 6

FIG. 5

FIG. 1 is a front elevational view of the toy racing trackway embodying my new design;

FIG. 2 is a rear elevational view thereof;

FIG. 3 is a top plan view thereof;

FIG. 4 is a bottom plan view thereof;

FIG. 5 is a left side elevational view thereof; and

FIG. 6 is a right side elevational view thereof.

The brackets shown in FIGS. 1-4 represent indeterminate length of the track member.

I claim:

The ornamental design for a toy racing trackway, as shown and described.
